CLAIM

The ornamental design for a display screen with a graphical interface, as shown and described.

DESCRIPTION

FIG. 1 is a perspective view illustrating a display screen with a graphical interface according to one embodiment;

FIG. 2 is a front view thereof;

FIG. 3 is a perspective view thereof, shown in a different placement in the environment;

FIG. 4 is a front view thereof;

FIG. 5 is a perspective view thereof, shown in a different placement in the environment;

FIG. 6 is a front view thereof;

FIG. 7 is a perspective view thereof, shown in a different placement in the environment;

FIG. 8 is a front view thereof;

FIG. 9 is a perspective view thereof, shown in a different placement in the environment;

FIG. 10 is a front view thereof;

FIG. 11 is a perspective view thereof, shown in a different placement in the environment;

FIG. 12 is a front view thereof;

FIG. 13 is a perspective view thereof, shown in a different placement in the environment;

FIG. 14 is a front view thereof;

FIG. 15 is a perspective view thereof, shown in a different placement in the environment;

FIG. 16 is a front view thereof;

FIG. 17 is a perspective view thereof, shown in a different placement in the environment; and,

FIG. 18 is a front view thereof.

The broken line showings of the display screen, rectangle, and triangle in all the figures are included for the purpose of illustrating environmental structure and portions of the display screen with a graphical interface. The broken lines form no part of the claimed design.
